ASYMMETRICAL BALANCE BEAM

Bojan Kriznic, Kusnacht, Zurich, Switzerland, assignor to
 Erhard Mettler, Zollikon, Zurich, Switzerland
 Filed July 18, 1961, Ser. No. 124,874
 Claims priority, application Switzerland Nov. 7, 1960
 7 Claims. (Cl. 177—246)

This invention relates to an asymmetrical balance beam for highly sensitive analytical or microbalances. Such balance beams consist of an edge arranged plate-shaped member forming the balance beam arms, a centre knife-edge fastened thereto, an end knife-edge on one of its arms, and a counterweight on the other of its arms. The two knife-edges extend perpendicular to the plane of the plate-shaped member and preferably project from rigid knife-edge supports, which are fastened to the plate-shaped member. The present invention aims to produce a balance beam of the aforementioned asymmetrical construction, the sensitivity of which, within certain limits, is independent of the ambient temperature.

The invention accordingly provides an asymmetrical balance beam of the type stated having a slot penetrating from the edge of said plate-shaped member in a direction transversely to the longitudinal direction of the balance beam, and a connecting member spanning said slot and holding together the two sections of the plate-shaped member on either side of said slot, said connecting member being made of a material having a linear coefficient of expansion different from that of the material of which said plate shaped member of the balance beam is made. Preferably, said connecting member is of H-shaped cross-section, the web of which fits into said slot, while the two parallel branches of the connecting member overlap externally the two sections of the balance beam on either side of said slot. If said slot is directed downwardly from the upper edge of the plate-shaped member, said connecting member must be made of a material which has a lower linear coefficient of expansion than the material of which said plate-shaped member is made.

These and other objects and the advantages of the invention will best be understood from the following description of a specific embodiment when read in connection with the accompanying drawing in which:

FIG. 1 shows a side view of an asymmetrical balance beam, and

FIG. 2 shows a top view of the balance beam shown in FIG. 1.

The balance beam has a plate-shaped member 3 of equal thickness throughout, which is provided intermediate its ends with a rigid knife-edge support 5 projecting from the bottom edge 4 of member 3. A downwardly extending central knife-edge 6 is fastened to the support 5, the knife-edge 6 extending in a direction transversely to the longitudinal direction of the balance beam. To the shorter arm 7 of the balance beam is fastened another, somewhat shorter knife-edge support 8, carrying an upwardly extending outer knife-edge 9 which is parallel to the knife-edge 6. The longer balance beam arm 10 has at its end a bolt 11, onto the threaded shank 12 of which is screwed a counterweight 13 comprising in the conventional manner a plurality of round discs. On the longer arm 10 beyond the bolt 11 there is fitted a socket 14 to hold a graduated or numbered dial plate 15 for reading the inclination of the balance beam when weighing, and thereby the last decimal figures of the object to be weighed.

The plate-shaped part 3 of the balance beam is made, as usual, of aluminium alloy, so that the weight of the whole beam is small. In the longer beam arm 10 and adjacent the centre knife-edge 6 a slot 17 is formed extending downwards from the upper edge 16 of the plate-

2

shaped member. As is shown in FIG. 1, the slot 17 extends to a height greater than half the height of the balance beam at the place of the slot 17. Into this slot 17 is inserted a connecting member 18 which, as shown in FIG. 2, is substantially H-shaped in cross-section. The web of this connecting member 18 fits into the slot 17 while the two parallel branches of the connecting member 18 span the slot 17, so that the two sections of the balance beam on either side of the slot 17 are overlapped 10 on the outside by the afore-mentioned branches of the member 17, as shown in FIG. 2. The two branches of the member 17 are attached to the adjacent parts of the balance beam, which they span, by cementing with synthetic resin and pinning. It is also possible to fasten 15 the connecting member 18 to the embraced parts of the beam by other means, provided that these give an intimate attachment which is able to sustain considerable shearing forces. As FIG. 1 shows, the height of the connecting member 18 is less than half the weight of the slot 17, and the connecting member 18 is arranged flush with the upper edge 16 of the plate-shaped member 3. The connecting member 18 is made of a material having a lower linear coefficient of expansion than the aluminium alloy of which the plate-shaped member 3 is made. A connecting member 18 of anti-magnetic stainless steel has been proved to be suitable; the linear expansion coefficient of such a steel is only about half that of the aluminium alloy used for balance beams. The connecting member 18 is further fastened to the two parts of the 20 balance beam on either side of the slot 17 in such a way that, at the normal temperature of for instance 20° C., no mechanical stresses arise within the balance beam.

If the temperature of the balance beam is increased, the area 19 of the balance beam between the lower end 35 of the slot 17 and the lower edge of the plate-shaped member 3 will expand more markedly than the connecting member 18. The latter exercises a tensile action which endeavors to raise the free end of the longer balance beam arm 10. At a higher temperature however, 40 the coefficient of elasticity also increases. The counterweight 13 causes flexural loading of the longer arm 10, the free end of which shows a tendency to move downwards. Thus the dimensions of the slot 17 and of the connecting member 18 can be adjusted in such a way 45 that these two aforementioned phenomena arising when the temperature is raised compensate for each other's effects to the extent that the sensitivity of the entire balance beam remains constant within broad limits. When the temperature drops, analogous reactions are produced 50 in the reverse sense. In this way it is possible to achieve virtually constant sensitivity of the balance beam within a temperature range of up to 60° C., i.e. for instance between -10° and +50° C., which includes all working temperatures which can reasonably be considered for an 55 analytical or micro balance.

In the embodiment in FIGS. 1 and 2 the slot 17 is directed downwards from the upper edge of the member 3. The slot 17 could also, however, extend upwards from the lower edge 4 of the plate-shaped member 3. In that 60 case, though, the connecting member 18 would have to be made of a material showing a greater coefficient of expansion than the material making up the plate-shaped member 3 of the balance beam. Supposing that an aluminium alloy is used for the member 3, a zinc connecting member 18 would be appropriate in view of the required coefficient of expansion. In view of its other mechanical properties, however, a connecting member 18 made of zinc would hardly appear to be suitable. For an aluminium beam, therefore, virtually the only possible construction is one in which the slot extends downwardly from the upper edge 16, as in FIGS. 1 and 2. In that case a fair number of materials having both the

required mechanical properties and a considerably lower coefficient of expansion than aluminium are available for the connecting member 18. Stainless and anti-magnetic steel and also titanium have shown to be the best materials for the connecting member 18.

The slot 17 could furthermore be made at a point in the balance beam other than that shown in FIGS. 1 and 2. For instance, practically the same effect could be produced by inserting the connecting member 18 into the balance beam flush with the upper part of the plate-shaped member 3 in an area above the centre knife-edge 6. But the connecting member 18 can also be further removed from the centre knife-edge 6 and placed approximately in the middle of the longer beam arm 10. It would also be possible to insert the connecting member 18 in the shorter beam arm 7. These and similar variants have the disadvantage, however, that the results sought are not achieved without stronger mechanical tensile and compressing forces arising, which in fact is undesirable. The most suitable place to insert the connecting member 18 is an area near to and above the central knife-edge 6 and still in the longer balance beam arm 10, as is already shown in FIGS. 1 and 2. Finally, the balance beam may also be provided with several slots in various places and connecting members inserted therein. These and similar modifications of the balance beam which may occur to those familiar with the art fall within the spirit and scope of the invention as set forth in the following claims.

I claim:

1. An asymmetrical balance beam for analytical or micro balances having an edge arranged plate-shaped member forming the balance beam arms, a centre knife-edge secured to said member, an end knife-edge on one of its arms and a counterweight on the other of its arms, said two knife-edges extending perpendicular to the plane of said plate-shaped member, said plate-shaped member having a slot penetrating from the edge of the plate-shaped member in a direction transversely to the longitudinal direction of the balance beam, and a connecting member spanning said slot and holding together the two sections on either side of said slot, said connecting member being made of a material having a linear coefficient of expansion different from that of the material of which said plate-shaped member of the balance beam is made.

2. The invention as recited in claim 1, wherein said connecting member is of H-shaped cross-section, the web

of which fits into said slot, while the two parallel branches of said connecting member overlap externally the two sections of the balance beam on either side of said slot.

3. The invention as recited in claim 1, wherein said slot and said connecting member are situated in an area near to the centre knife-edge on the longer balance beam arm, said longer balance beam arm having the counterweight.

4. An asymmetrical balance beam for analytical or micro balances having an edge arranged plate-shaped member forming the balance beam arms, a centre knife-edge secured to said member, an end knife-edge on one of its arms and a counterweight on the other of its arms, said two knife-edges extending perpendicular to the plane of said plate-shaped member, said plate-shaped member having a slot which is directed downwardly from the upper edge of said plate-shaped member, and a connecting member spanning said slot and holding together the two sections on either side of said slot, said connecting member being made of a material having a lower linear coefficient of expansion than the material of which said plate-shaped member is made.

5. The invention as recited in claim 4, wherein said plate-shaped member is made of an aluminium alloy and said connecting member of anti-magnetic stainless steel.

6. An asymmetrical balance beam for analytical or micro balances having an edge arranged plate-shaped member of equal thickness forming the balance beam arms, a centre knife-edge secured to said member, an end knife-edge on one of its arms and a counterweight on the other of its arms, said two knife-edges extending perpendicular to the plane of said plate-shaped member, said plate-shaped member having a slot penetrating from the edge of the plate-shaped member over a height at least equal to half the height of the balance beam in the region of said slot, and a connecting member spanning said slot and holding together the two sections of said plate-shaped member on either side of said slot, said connecting member being made of a material having a linear coefficient of expansion different from that of the material of which said plate-shaped member is made.

7. The invention as recited in claim 6, wherein the height of said connecting member is less than half the height of said slot, and also said connecting member is arranged on one side flush with the edge from which said slot penetrates.
